MACHINE FOR ASSEMBLING OPHTHALMIC MOUNTINGS

Samuel E. Bouchard, Rochester, N. Y., assignor to Bausch & Lomb Optical Company, Rochester, N. Y., a corporation of New York

Application August 30, 1934, Serial No. 742,082

4 Claims. (Cl. 219—4)

This invention relates to machines for assembling ophthalmic mountings by the application of heat and pressure and more particularly to devices for locating the mountings in the machine. 5 The present invention is particularly adapted for machines such as the machine for assembling ophthalmic mountings, disclosed and claimed in my co-pending application Serial No. 620,452 filed July 1, 1932, since matured into Patent No. 10 1,978,890, dated October 30, 1934.

One of the objects of my invention is to provide an efficient and improved device by which ophthalmic mountings of different types may be rapidly and accurately positioned and assembled 15 by the application of heat and pressure. Other objects and advantages reside in certain novel features of construction, arrangement and combination of parts as will hereinafter be more fully described and pointed out in the appended claims.

20 Referring to the drawing:

Fig. 1 is a side elevation of a machine embodying my invention.

Fig. 2 is a front view of same.

25 Fig. 3 is a detail view showing my invention in use with one type of ophthalmic mounting.

Fig. 4 is a detail view showing my invention in use with another type of ophthalmic mounting.

30 Fig. 5 is a detail view showing one form of improved positioning member.

Fig. 6 is a section taken on line 6—6 of Fig. 5.

One embodiment of my invention is shown in the drawing in which 10 indicates a base having an integral arm 11 upon which an arm 12 is 35 pivotally mounted as at 13. The column 11 has an integral portion 14 upon which is fixedly mounted a T-shaped block 15 which is made of hard rubber, fiber or the like for a purpose to be hereinafter described.

40 Fixedly mounted upon the block 15 is an arm 16 which carries a bearing member 17 upon which is mounted a multiple jaw 18. The multiple jaw 18 has a plurality of plane, work supporting surfaces 19, and a limiting disk 20 perpendicular to the work supporting surfaces 19. A plurality of positioning slots 21, 22, 23 and 24 are formed in the limiting disk 20, each slot cooperating with a particular work supporting surface for positioning the work. The slots 21 and 24 are 45 located substantially centrally of their respective cooperating supporting surfaces 19, the former for positioning the end pieces or bridges of conventional mountings 25 such as shown in Fig. 3, while the latter is used for positioning conventional studs. The slots 22 and 23 are positioned

away from the center of their respective cooperating supporting surfaces 19 for positioning respectively the left and right hand end pieces for high temple mountings 26 such as shown in Fig. 4. A leaf spring 27 carries a pin 28 for engaging one 5 of the locking holes 29 in the multiple jaw 18 for holding the jaw in desired position. An enlarged head 30 permits the operator to withdraw the pin when it is desired to bring a different slot into operative position. Adjustably secured to the 10 arm 12 by means of a screw 31 is a jaw member 32 which extends downwardly and outwardly as shown in Figs. 1 and 2 and serves to clamp the mounting against the multiple jaw 18.

Slidably mounted on the free end of the arm 15 12 is a plunger 33 having a finger piece 34 urged upwardly by a coil spring 35. A conducting arm 36 mounted on the block 15 and insulated from the arm 16, carries a conducting screw 37 below and in direct alignment with the plunger 33 said 20 screw 37 further supporting the ophthalmic mounting. A spring 38 connecting the projection 14 and arm 12 tends to normally urge the arm downwardly to bring jaw 32 down toward multiple jaw 18. Pivotally mounted on block 15 25 is a lever 39 having a cam surface 40 by means of which the arm 12 together with the jaw 32 may be raised upwardly against the action of the spring 38.

30 Mounted upon the base 10 is a suitable transformer 41 which is connected to a source of electrical energy by means of a wire 42. Leading out from the transformer 41 are two wires 43 and 44, the first of which is connected to the arm 12 while the second is connected to the arm 36. 35 Since arm 36 is mounted upon the block 15, made of hard rubber, fiber or the like, it is electrically insulated from both arm 12 and arm 16.

My device is intended for use in assembling 40 rimless ophthalmic mountings of the type shown having a pair of lens engaging straps 45, 46, a shoe 47 engaging the edge of the lens and a connection 48 extending outwardly from the shoe 47. This connection may be either the bridge or the temple connection as the procedure is the same 45 for either. In Fig. 4 a type of connection is shown for the high temple end pieces where the temples are located above the eye level.

In using the device, the pin 28 is withdrawn from the hole 29 and the multiple jaw 18 rotated 50 until the desired slot is in operative position. The pin 28 is then inserted in the hole 29 and the multiple jaw 18 locked against rotation. An ophthalmic mounting, for example 25, is then placed in the machine with the strap 45 resting 55

upon the supporting surface 19 and the conducting supporting screw 37, the shoe 47 pressed against the limiting member 20 and the connection 48 held in the positioning slot 21. The lever 39 is then lowered and the mounting is firmly clamped between jaw 32 and the multiple jaw 18. A fusible plug is then inserted in the mounting, the mounting is heated and the plug forced into the mounting to securely hold the lens in the mounting as fully set forth in my aforesaid co-pending application.

In assembling the mounting the plug may be of any suitable material such as a plastic cellulosic material or a metal or metal alloy of relatively low melting point. When a metallic plug is used, the jaw 32 can be omitted and the heating current passed through the plunger 33, the plug and the screw 37 while the mounting is held in the multiple jaw by hand. In such a case the arm 12 could be fixed to the block 15. The multiple jaw 18 is shown as having a plurality of surfaces 19 rotatable with the disk 20 but obviously the disk 20 could be rotatable with respect to a single surface 19 and still perform its function in the same way. Obviously also the disk 20 could as well be a slidable slotted plate.

From the foregoing it will be apparent that I am able to attain the objects of my invention and provide an improved device for assembling ophthalmic mountings by the application of heat and pressure and an improved device for locating the mountings therein. Various modifications can obviously be made without departing from the spirit of my invention.

I claim:

1. In a device for attaching ophthalmic mountings, a pivoted guide member having a plurality of plane mounting supporting surfaces parallel to its pivotal axis, a plane surface extending perpendicularly beyond each of said plane supporting surfaces and a radial slot in each of said plane surfaces extending from the peripheral edge of the plane surface to said plane supporting surface.
2. In a device for attaching ophthalmic mountings or the like, a rotatably mounted supporting member having a plurality of plane, angularly

related supporting surfaces disposed about its periphery in planes parallel to its axis of rotation, a disk fixed to said member and having a plane surface perpendicular to the axis of rotation adjacent said member and extending beyond said member on all sides, guide slots in said disk extending from the periphery of the disk perpendicularly to some of the supporting surfaces of said member, said slots being of different size and position to accommodate different types of articles, means for rotating said member and said disk to bring the selected supporting surface and slot into operative position, and means for securing said member and said disk in the selected position.

3. In a device for attaching ophthalmic mountings which have spaced, lens engaging straps, a shoe for contacting with the edge of a lens and a connection extending outwardly from the shoe, a positioning means comprising a supporting member adapted to support a strap, a movably mounted limiting member having a shoe engaging surface adjacent said supporting member and perpendicular thereto, said limiting member being provided with a positioning slot for a connection, means for adjusting said movable member to accommodate connections positioned at different angles to the shoe and means for fastening said movable member in adjusted position.

4. In a device for attaching ophthalmic mountings which have spaced, lens engaging straps, a shoe for contacting with the edge of a lens and a connection extending outwardly from the shoe, a positioning means comprising a rotatably mounted element having a plurality of angularly related strap supporting faces in planes parallel to the axis of rotation, a shoe limiting member for each supporting face and perpendicular thereto, a connection positioning slot in each limiting member perpendicular to the supporting surface, some of said slots being positioned to accommodate high temple connections, means for rotating said element for selecting the face, member and slot for the particular work and means for locking said element in selected position.

SAMUEL E. BOUCHARD.
